United States Patent Office.

THOMAS DOLAN, OF PHILADELPHIA, PENNSYLVANIA.

Design No. 3,966, dated April 12, 1870.

DESIGN FOR STOCKING FABRIC.

The Schedule referred to in these Letters Patent and making part of the same.

I, THOMAS DOLAN, of Philadelphia, county of Philadelphia, State of Pennsylvania, have invented or produced a Design for a Stocking Fabric, of which the following is a specification.

The figure in the accompanying drawing represents my design for a stocking fabric, the main features of which consist of two stripes A A, each of which is composed of a vertical row of diamond-shaped spots, *a a*, bounded by a zig-zag edging, *b*.

Between the spots *a*, and forming part of the edging, are small dots *c c*.

On each side of the above are arranged zig-zag ribs *d e f*, and intervening diamond-shaped spots *g* and *h*, in the manner clearly represented in the drawing.

Between the stripes A A are two narrow zig-zag ribs *i i*, so arranged in respect to each other as to form between them the diamond-shaped spaces represented

Irrespective of the colors employed, I claim—

The design for a stocking fabric, substantially as described, and as represented in and by the accompanying drawing.

In testimony whereof I have signed my name to this specification in the presence of two subscribing witnesses.

THOMAS DOLAN.
